upon-Tyne, England

Application March 8, 1949, Serial No. 80,244
In Great Britain December 12, 1947

4 Claims. (Cl. 257—6)

1

This invention relates to combustion turbines of all types embracing those in which the working fluid may be obtained from a solid, liquid, or gaseous source, for instance, gas, oil, or coal, and which may be produced either internally or externally.

The invention particularly relates to sealing devices in exchangers of the rotary heat accumulative type, sometimes called the regenerative type. Such exchangers are used in combustion turbine power units for transferring the heat between the hot gases and the compressed air before it is heated in the combustion chamber.

In a heat exchanger of this type the heat is transferred by passing the hot gases through one half of a rotating drum containing heat transfer surfaces and by passing the air to which the heat is to be transferred through the other half of the drum. It is usual for the air to pass through one half of the exchanger after delivery from the compressor and it is therefore, at a high pressure, while the gases are passed through the other half of the exchanger after exhausting from a turbine and are, therefore, at a lower pressure than the air.

The object of this invention is to provide a method of sealing between the two parts of the exchanger as the rotating drum passes from the low pressure gas side to the high pressure air side, and vice versa.

Referring to the accompanying diagrammatic drawings:

Figure 1 is a longitudinal sectional elevation of a regenerative heat exchanger of the rotating drum type;

Figure 2 is a transverse section on the line 2—2 of Figure 1 looking in the direction of the arrows;

Figure 3 illustrates forces acting on the shoes when a chamber passes underneath them, the position being one of maximum pressure;

Figure 4 is similar to Figure 3 with the drum moved a certain distance on, the position being one of intermediate pressure, and

Figure 5 is similar to Figures 3 and 4 with the drum still further moved forward, the pressure being the condition of minimum pressure;

Figure 6 is a diagram showing the relationship between periodicity on the horizontal axis and, on the vertical axis force or pressure at different times;

Figure 7 illustrates diagrammatically a control system for use according to one form of the present invention.

In carrying the invention into effect in one

form by way of example and referring first more particularly to Figures 1 and 2, the exchanger consists of an outside casing *a* which is divided into two parts by seals *b*. There is a gas inlet connection at *c* and an air outlet connection at *d*. Inside this casing an annular drum *e* is rotated. A second and internal casing *f* is fitted inside the drum *e* so that the interior space is divided into two sections by seals *g* in such a way as to provide axial openings at the ends of the casings for the air inlet and gas outlet connections. The drum *e* which is supported by means of ball bearings *h* on the inner casing *f* is divided into several separate axial chambers by the ribs *i*. The chambers are filled with suitable heat transfer surfaces *j*, such as wire gauzes, and holes are provided in the inside and outside walls of the drum so that the gases and air can flow through the drum. The seals *b* and *g*, between the air and gas sides of the drum, consist of shoes of such a shape that they slide on the outside and inside surfaces of the drum, and are of sufficient width to cover one complete chamber of the drum. The shoes are pressed up against the surface of the drum by push rods *k* and *l* to which pressure is applied by means of flexible metal tubes *m* and *n* which are filled with oil or other substantially incompressible fluid. The tubes are supported in the outside and inside casings *a* and *f* respectively.

30 The tubes *m* and *n*, which are of similar construction, consist, in one form, of thin gauge tube of approximately oval section extending over the entire length of the shoes. The two ends of the tubes are tightly closed in such a manner that the end pieces do not affect the flexibility of the tube at the position of the ends of the shoes. If the ends are of a type which are incapable of flexibility they can be connected to the flexible part of the tube by means of a bellows connection or similar flexible joint.

35 In the operation of the exchanger the drum is rotated by an external means so that given chambers of the drum will, at one stage, be completely covered by the external and internal shoes bearing on the drum surfaces.

40 Referring now to Figures 3, 4 and 5 which show the forces acting on the shoes when such a chamber passes underneath them, in Figure 3 the one rib of the chamber has just cleared the shoes on the high pressure side of the exchanger, thereby exposing the chamber to the air pressure in this side. The pressure in the chamber, therefore, rises immediately to the air pressure and acts on 45 the portion of the shoes covering the chamber.

50

As the drum rotates, for instance until it reaches the position shown in Figure 4, the portion of the chamber subjected to the high pressure air and exerting a high force on the shoes, is decreased while the portion of the neighbouring chamber, which has been exposed to the low pressure gas, and is, therefore, exerting a low force on the shoes, is increasing. Finally, the position shown in Figure 5 is reached in which the rib between these two chambers reaches the edge of the shoes on the high pressure side of the exchanger and no further influence is exerted on the shoes by the high pressure air. The force, $P_{\min}$, then acting on the shoes, is given by the pressure of the low pressure gases. This cycle is then repeated as each chamber passes under the shoes.

Two periods o and p are illustrated in Figure 6. The maximum pressure occurs at the point q . Intermediate pressure is indicated by the line r and minimum pressure by the horizontal line s .

In order that the shoes should provide a seal between the high pressure and low pressure parts of the exchanger, a force must be provided equal to that exerted by the air or gas pressure in the chambers under the shoes. If a constant external pressure is supplied, it would have to be equal to that necessary to counteract the greatest force $P_{\max}$ exerted by the high pressure air, but as the pressure exerted on the shoe by the air or gases in the chambers decreased, the remainder of the constant external force would produce a very high friction force, so that considerable power would be required to drive the drum. This invention reduces the power required to drive the drum by influencing the external pressure on the shoes to correspond with that being exerted by the air or gases in the chambers passing under the shoes.

The oil tubes m and n are, to this end, connected to a suitable control system and oil pressure supply, such as a pump, supplying a constant pressure to the system.

Referring to Figure 7, the control system consists of a pump q supplying oil, at a pressure which is maintained constant by a relief valve r to non-return valves whence the oil is divided in the flexible sealing oil tubes m and n . The oil in the tubes is also connected through orifice valves t back to the supply side of the non-return valves s .

In operation, oil of comparatively low pressure flows through the non-return valve during the part of the cycle when the force on the shoes is smallest, that is during the period when the force is $P_{\min}$ (Figure 5), thereby filling the oval tubes m and n and bringing the shoes into contact with the drum e . As soon as the gas loading on the shoe increases, the tubes m and n tend to be compressed and displace oil back into the supply system. When the oil pressure in the tubes m and n rises above that set according to the relief valve r , the non-return valves s close and the oil pressure in the tubes then increases according to the applied force on the shoes. The orifice valves t are provided for the purpose of draining a small quantity of oil out of the system to allow for changes in volume of the tubes due to changes in dimensions of the casing and the drum under operating pressures and temperatures. When the non-return valve is closed, there is a bleed through

the orifice valves from the tubes to the supply side of the non-return valves, and, therefore, the shoes can lift from the drum. The bleed is adjusted so that the degree of lift is very small, and does not materially affect the sealing properties.

We claim:

1. In a regenerative heat exchanger having an annular rotor with longitudinal partitions dividing it into circularly arranged matrix holding chambers and stationary elements for defining two separated passages for gas flow through the rotor, the said chambers being open for gas flow between the said partitions both on the inner and outer peripheral surfaces of the rotor and in combination, sealing devices between the said stationary elements and the inner and outer peripheral surfaces of the rotor for sealing the two said passages from each other, each said sealing device comprising a sealing shoe for forming a seal between the two said passages, the sealing shoe having a rotor-engaging surface of arcuate extent sufficient to cover a complete rotor chamber, means mounting the shoe for radial movement toward and away from the rotor, and means for holding the shoe in sealing engagement with the rotor, the last said means comprising a flexible tube, means supporting the tube and compressing it against the shoe for forcing the shoe toward the rotor, and means for keeping the tube full of incompressible liquid and varying the pressure of the said liquid in accordance with variation in gas pressure against the surface of the shoe as the rotor compartments pass the same, whereby the force exerted against the shoe by the said tube maintains a substantially constant and relatively small sealing pressure of the shoe against the rotor.
2. The combination according to claim 1, in which the said tube is a thin walled metal tube.
3. The combination according to claim 1, in which the means for keeping the shoe filled with liquid and varying the pressure of the said liquid comprises a source of supply of incompressible liquid under substantially constant pressure, a non-return valve connecting the tube to the said source of supply and a restricted orifice also connecting the tube to the said source of supply.
4. The combination according to claim 3, in which the said tube is a thin walled metal tube.

ANDREW THOMSON BOWDEN,
WALDEMAR HRYNISZAK,
PAUL KOLB.
